UNITED STATES PATENT OFFICE.

JOSEPH N. DE WINTER, OF NEW YORK, N. Y.

FLUID-EXPLODED ORDNANCE.

1,324,733.

Specification of Letters Patent. Patented Dec. 9, 1919.

Application filed November 6, 1918. Serial No. 261,378.

To all whom it may concern:

Be it known that I, JOSEPH N. DE WINTER, residing at New York, in the county of New York and State of New York, have invented 5 new and useful Improvements in Fluid-Exploded Ordnance, of which the following is a specification.

This invention relates generally to fluid exploded ordnance.

10 An object of the invention is to provide a gun in which the maximum of power can be obtained and directly spent against the shell, while practically eliminating the dangers of firing.

15 Another object of the invention resides in the construction of a gun in which the barrel and breech are designed to accommodate ordinary shells or projectiles without requiring any changes in the construction 20 thereof in order to effectuate a perfect firing.

A still further object of the invention is to provide a fluid exploded gun which will consist generally of a barrel having a fluid confining chamber, mechanism for supplying a charge of fluid to the chamber and for compressing the same, the valve mechanism at the breech for causing the compressed charge when exploded to be entirely spent against the shell.

30 A still further object of the invention pertains to a novel combination of parts which, while permitting of a maximum expenditure of force against the shell will be of an extremely compact and simple nature.

35 A still further object of the invention is to provide a gun including a valve at its breech adapted to be opened to a firing chamber, and a breech block separable from the valve whereby to permit of the loading of the gun from the breech.

Another object of the invention is to provide a gun in which novel means will be employed for compressing an explosive 45 charge and for exposing the shell to the action of the charge at the requisite moment, and with despatch and facility.

With the above and other objects in view which will appear as the nature of the invention is better understood, the same consists in the improved construction and novel arrangements of parts which will herein-after be fully described and particularly pointed out in the claims.

55 In the accompanying drawings, has been illustrated, a single and preferred form of

the invention, it being however, understood that no limitations are necessarily made to the precise structural details therein exhibited, but that changes, alterations and modifications within the scope of the claims may be resorted to when desired.

Figure 1 is a vertical longitudinal section through the gun.

Fig. 2 is a similar view of the breech of the gun with the valve removed.

Fig. 3 is a side view of the valve.

Fig. 4 is a side view of the breech block.

Fig. 5 is a front view of the pins or keepers for the breech block.

In devising the gun which will be presently explained in full detail, I have endeavored to provide a construction and mechanism wherein the barrel will adapt itself to shells or projectiles of ordinary 75 construction. I have also perfected an arrangement whereby atmospheric air can be compressed and exploded in the presence of the shell, while at the same time taking into consideration the possible use and perhaps 80 efficiency at times of various explosive charges, other than powder, such as vaporized gasoline or other volatile substance. I wish also to emphasize the importance of compactness of parts, the ease, facility and 85 despatch with which the entire mechanism can be operated with the minimum possibility of danger and with a creation of a high measure of force against the shell.

The invention both broadly and specifically will now be described as follows:

10 represents the barrel of the gun of the straight bore type, said barrel including spaced heads 11 and 12 at the breech of the gun and a connecting cylinder 13 between 95 the heads. Adjacent to the forward end of the barrel is a third head 14 and the latter, together with the previously mentioned heads 11 and 12, are embraced by a cylindrical jacket or shell 15. In this manner 100 the structure is divided into a compressing chamber 16 and an exploding or firing chamber 17. The heads 11, 12 and 14 may be secured to the shell 15 in any suitable well known manner but I prefer to bolt the same 105 thereto as at 18 and provide packing gaskets 19 between the peripheral faces of the several heads and the inner walls of the shell 15. In this manner the respective chambers 16 and 17 are rendered fluid tight except to 110 some minor extent in the chamber 16 for a purpose to be hereinafter explained.

The connecting cylinder 13 opens directly to the barrel and it is provided with portways 20 which open to the chamber 17. The head 12 is provided with intake valves 21 which are designed to establish communication between the chambers 16 and 17 at certain intervals of operation of the mechanism. These valves open in the direction of the chamber 17 and are closed in an opposite direction by springs 22. Sliding over the barrel 10 is a piston 23 having a lateral head 24 which operates as a compressor. The piston head is provided with packing gaskets 25 which impinge against the inner walls of the chamber 16. The chamber 16 is provided with an intake valve 26 which is adapted to communicate with a source of fuel supply when gasoline or other motive fluid is employed and which is arranged to open directly to the atmosphere when it is desired to use atmospheric charges as an explosive medium. It will be observed incident to this construction that on the stroke of the piston in the direction of the arrow (a), the fluid 25 will be drawn into the chamber 16 between the piston head 24 and the barrel head 12 and that on a reverse operation of the piston, the charge taken in will be compressed and forced past the valves 21 into the chamber 17, ready to be fired in a manner to be described hereinafter. Any suitable well known mechanism may be employed for reciprocating the piston. One mode of accomplishing the desired result resides in the provision of a rack surface 27 on the piston, a pinion 28 on a driven shaft 29 and a power transmitting wheel 30. The latter may be of a design to be driven by hand, motor or otherwise as this is immaterial as long as the requisite power is supplied to the shaft 29. What mechanism is employed, however, must permit of opposite reciprocal movements of the piston.

Within the cylinder 13 defined by the connecting portion of the barrel between the respective heads 11 and 12, is a rotary valve 31 having annular gaskets 32 adapted to engage against the bore of said cylinder to normally establish an air tight connection. The valve is provided with portways 33 which are adapted to register with the portways 20 when the valve is adjusted to one position. When adjusted to another position the portways 20 and 33 are closed with respect to each other and as a consequence thereof no communication is established between the barrel of the gun and the charge exploding chamber 17. This valve may be rotated by hand and for this purpose it is provided at its butt end with a manipulating extension or handle 34. Within the chamber 17 is a firing mechanism 35 in the form of a spark plug, while on the rotary valve is a contact member 36 in the form of an adjustable screw which is adapted to co-

act with the spark plug to respectively make and break the circuit. The head 11 is provided with keeper openings 37 which are adapted to register with slots 38 in the rotary valve. A breech block 39 is insertible in the valve and the same is provided with radially movable pins 40 which are adapted to be retracted with respect to the slots 38 and the keeper recesses 37 and which are arranged when engaged in the latter to hold the block firmly in position to effectuate the action of the explosive charge on firing. Within the breech block are rotary controlling pinions 41 which engage the rack teeth 42 of the sliding pins. These pinions are actuated by a hand lever 43 located at the rear of the breech block.

A suitable gage 44 is connected with the chamber 16 whereby the operator can readily determine the state of compression of the fluid under the action of the reciprocating piston when the valves 21 are opened.

Having described the principal details of construction of the gun, the operation thereof is set forth as follows: The fluid capable of being fired on compression when sucked past the intake valve 26 under the action of the piston head 24 in one direction will, on an operation in the reverse direction of the piston head be compressed and simultaneously made to enter the chamber 17. In the latter, the compressed charge is stored until it is desired to fire the gun, at which time the valve 31 is rotated whereby to open the portways 20 and 33 relatively simultaneously with an engagement of the contact member 36 with the firing mechanism 35. It is, of course, understood that the breech block 37 permits of a loading of the gun from the breech. It is further seen that when in position, the butt of the shell will be located immediately in advance of the portways 20. Assuming that the breech block is in a fixed position and the valve 31 rotated as just described above, the projectile or shell will be fired from its barrel under the explosive action of the compressed charge.

In the drawing, it will be observed that the head 14 is not in air tight connection with the piston 23 and that said head is provided with a central bore 14^a, through which the piston is slid able. The diameter of the bore sufficiently exceeds the outside diameter of the piston so as to establish an exhaust port for the discharge of the air at the side of the piston on the return stroke thereof.

When a hydrocarbon is used I find that its measure of efficiency as an explosive agent can be increased through surrounding the compression chamber about the barrel so that the heat from the latter and adjacent surfaces of the structure will accelerate the volatilization of the fluid and thus render the compressed charge more effective.

What is claimed as new is:

1. A gun of the class described comprising a barrel having ports in its breech end, a chamber surrounding said end and in communication with the ports, a valve for controlling said ports, means for introducing an explosive mixture into said chamber, firing means in said chamber and means for actuating the firing means and the valve simultaneously. 70
2. A gun of the class described comprising a barrel having ports in its breech end, a firing chamber surrounding said end and in communication with the ports, a compressing chamber in communication with the firing chamber, valves for controlling such communication, means in the compressing chamber for drawing an explosive mixture thereinto and for compressing the same and discharging it into the firing chamber, a valve controlling the ports, firing means in the firing chamber and means for simultaneously operating said means and the valve. 80
3. A gun comprising a barrel having surrounding normally non-communicating fluid compressing and fluid exploding chambers respectively, means for establishing communication between said chambers to permit of the receipt and retention by the exploding chamber of a compressed fluid charge, and means in the barrel normally separating the projectile to be fired from the exploding chamber and operable to directly subject the projectile to the action of an exploding charge in said chamber. 90
4. In a gun of the class described, the combination with a barrel having a compression chamber, and an exploding chamber, the latter embodying means for permitting of the reception of a compressed explosive fluid in said exploding-chamber, a piston reciprocating over the barrel and working in said compression chamber, and means normally closing the exploding chamber to the barrel and adjustable to permit of communication of the barrel with said chamber. 100
5. In a gun of the class described, a barrel having a portway at its breech and a surrounding exploding chamber, means for compressing a fluid charge in said chamber, and a ported valve mounted in the breech of the barrel, said valve co-acting with the portway in the barrel and serving to open the barrel to the exploding chamber. 110
6. In a gun of the class described, a barrel having a portway at its breech and an exploding chamber, means for compressing a fluid charge in said chamber, a rotary valve in the breech of the gun provided with a portway co-acting with the portway of the barrel, and a removable breech block mounted in one end of the valve and serving when removed to permit of a breech loading of the barrel. 120
7. In a gun of the class described, a barrel having a portway at its breech and an exploding chamber surrounding the ported portion of the barrel, a rotary valve at the breech of the barrel, said valve ported to co-act with the portway of the barrel, a breech block insertible in one end of the valve and including mechanism for effecting its locked condition with the barrel and a relatively free condition with the valve, and means for supplying the exploding chamber with an explosive charge. 125
8. In a gun of the class described, a barrel having a portway at its breech and an exploding chamber surrounding the ported portion of the barrel, a rotary valve at the breech of the barrel, said valve ported to co-act with the portway of the barrel, a breech block insertible in one end of the valve and including mechanism for effecting its locked condition with the barrel and a relatively free condition with the valve, means for supplying the exploding chamber with an explosive charge, firing mechanism in the exploding chamber, and means operable on rotation of the valve to align the mentioned portways for actuating said firing mechanism. 130
9. In a gun of the class described, a barrel having a portway at its breech and an exploding chamber surrounding the ported portion of the barrel, a rotary valve at the breech of the barrel, said valve ported to co-act with the portway of the barrel, a breech block insertible in one end of the valve and including mechanism for effecting its locked condition with the barrel and a relatively free condition with the barrel and a relatively free condition with the valve, means for supplying the exploding chamber with an explosive charge, firing mechanism in the exploding chamber and means carried by the valve for actuating said firing mechanism. 140
10. In a gun of the class described, a barrel having a portway at its breech and an exploding chamber surrounding the ported portion of the barrel, a rotary valve at the breech of the barrel, said valve ported to co-act with the portway of the barrel, a breech block insertible in one end of the valve and including mechanism for effecting its locked condition with the barrel and a relatively free condition with the barrel and a relatively free condition with the valve, means for supplying the exploding chamber with an explosive charge, firing mechanism in the exploding chamber, means carried by the valve for actuating said firing mechanism, the former disposed in the path of movement of the latter as the valve is rotated. 150
11. In a gun of the class described, a barrel having surrounding fluid compressing and fluid exploding chambers respectively, 160

valves between said chambers, a valved intake leading to the compressing chamber, a piston operating in said compressing chamber and including a rack surface, power transmitting mechanism co-acting with said rack surface to reciprocate the piston, and mechanism normally sealing the barrel from the exploding chamber and adapted to establish communication therewith.

10. 12. In a gun of the class described, a barrel having surrounding fluid compressing and fluid exploding chambers respectively, valves between said chambers, a valved intake leading to the compressing chamber, a piston operating in said compressing chamber and including a rack surface, power transmitting mechanism co-acting with said rack surface to reciprocate the piston, mechanism normally sealing the barrel from the 15 exploding chamber and adapted to establish communication therewith, said communication establishing mechanism embodying a ported breech end of the barrel and a rotary valve mounted in the breech.

16. 13. In a gun of the class described, a barrel having surrounding fluid compressing and fluid exploding chambers respectively, valves between said chambers, a valved intake leading to the compressing chamber, a piston operating in said compressing chamber and including a rack surface, power transmitting mechanism co-acting with said rack surface to reciprocate the piston, mechanism normally sealing the 20 barrel from the exploding chamber, and adapted to establish communication therewith, said communication establishing mechanism embodying a ported breech end of the barrel, a rotary valve mounted in the 25 breech, and a breech block insertible in one end of the valve and having means for locking connection with the barrel.

14. A gun of the class described comprising a barrel having an exploding chamber, the breech of the barrel ported to the exploding chamber, a cylindrical rotary ported valve working in the barrel and co-acting with the ported breech thereof, the forward end of the valve opening toward 45 the front of the barrel, and a block closing the rear end of the valve.

15. A gun of the class described comprising a barrel having an exploding chamber, the breech of the barrel ported to the exploding chamber, a cylindrical rotary ported valve working in the barrel and co-acting with the ported breech thereof, the forward end of the valve opening toward 50

the front of the barrel, a block closing the rear end of the valve, and removably connected with the barrel to permit the barrel to be loaded from the breech and through the valve.

16. A gun of the class described comprising a barrel having an exploding chamber, the breech of the barrel ported to the exploding chamber, a cylindrical rotary ported valve working in the barrel and co-acting with the ported breech thereof, the forward end of the valve opening toward the front of the barrel, a block closing the rear end of the valve and removably connected with the barrel to permit the barrel to be loaded from the breech and through the valve, means for supplying the exploding chamber with an explosive charge, firing mechanism for said exploding chamber, and means operable on movement of the valve to open the barrel to the exploding chamber for actuating said firing mechanism.

17. In a gun of the class described, a barrel, a casing encircling said barrel and subdivided to provide a fluid compressing chamber and an exploding chamber, valve means between said chambers, a valved fluid intake for the compressing chamber, and a valve for opening the barrel to said explosive chamber.

18. In a gun of the class described, a barrel, a casing encircling said barrel and subdivided to provide a fluid compressing chamber and an exploding chamber, valve means between said chambers, a valved fluid intake for the compressing chamber, a valve for opening the barrel to said explosive chamber, said last valve mounted for rotation in the barrel at the breech thereof.

19. A gun of the class described comprising a barrel having valve separated compressing and exploding chambers respectively, means for taking in a supply of fluid to said compressing chamber and for compressing the same in the exploding chamber, a cylindrical valve mounted to rotate in the breech of the barrel, said valve having a portway, the breech of the barrel having a portway adapted to register with the first named portway when the valve is adjusted to one position, the portway in the barrel leading to the exploding chamber, and means for closing the rear end of the rotary valve.

I testimony whereof I have affixed my signature.

JOSEPH N. DE WINTER.
